United States Patent Office

Des. 177,657
Patented May 15, 1956

177,657

TABLE

Harry A. Bedol, Cleveland Heights, Ohio

Application August 26, 1955, Serial No. 37,680

Term of patent 14 years

(Cl. D33—14)

Fig. 3

Fig. 1

I claim:

The ornamental design for a table, substantially as shown.
